CLAIM

The ornamental design for a connector for rod-like lighting elements, as shown and described.

DESCRIPTION

FIG. 1 is a left side view of the connector for rod-like lighting elements;

FIG. 2 is a front view of the present invention, a connector for rod-like lighting elements;

FIG. 3 is a right side view of the present invention, a connector for rod-like lighting elements;

FIG. 4 is a back view of the present invention, a connector for rod-like lighting elements;

FIG. 5 is a top plan view of the present invention, a connector for rod-like lighting elements;

FIG. 6 is a bottom plan view of the present invention, a connector for rod-like lighting elements; and,

FIG. 7 is a perspective view of the present invention, a connector for rod-like lighting elements.
